No. 616,930.

Patented Jan. 3, 1899.

J. R. JONES.

WIRE AND PICKET FENCE MACHINE.

(Application filed Sept. 30, 1897.)

(No Model.)

UNITED STATES PATENT OFFICE.

JAMES R. JONES, OF WATERFORD, MICHIGAN.

WIRE-AND-PICKET-FENCE MACHINE.

SPECIFICATION forming part of Letters Patent No. 616,930, dated January 3, 1899.

Application filed September 30, 1897. Serial No. 653,564. (No model.)

To all whom it may concern:

Be it known that I, JAMES R. JONES, a citizen of the United States, residing at Waterford, county of Oakland, State of Michigan, have invented a certain new and useful Improvement in Fence-Machines; and I declare the following to be a full, clear, and exact description of the invention, such as will enable others skilled in the art to which it applies to make and use the same, reference being had to the accompanying drawings, which form a part of this specification.

This invention has for its object certain new and useful improvements in a fence-machine; and it consists of the construction, combination, and arrangement of devices hereinafter set forth and claimed, and illustrated in the accompanying drawings, in which—

Figure 1 is a view in side elevation illustrating my invention. Fig. 2 is a front elevation. Fig. 3 is an elevation from the opposite side of the machine. Fig. 4 is a detail view of the bearing of one of the twisting-wheels. Fig. 5 is a detail view of one of the sprocket-wheels in elevation. Fig. 6 is a view in section on the line 6 6, Fig. 3. Fig. 7 is a view in section on the line 7 7, Fig. 3. Fig. 8 is a detail view showing the portion L' with the open loops at its extremities. Fig. 9 is a detail view of the eyebolt m, embracing the bar M.

This invention belongs to that class of fence-making machines by which sets of longitudinal wires are twisted about a picket, the object of the machine being to twist the longitudinal strands about the picket and about one another in the formation of the fence.

The invention is carried out as follows:

A represents any suitable vertical framework provided with a bearing A', in which is journaled a driving-shaft B, provided with an operating-handle B'. The driving-shaft is provided with a pinion B², meshing with a gear C upon a shaft C', said shaft journaled in a bracket D, engaged upon the frame A. Upon the shaft C' is a sprocket-wheel C².

E represents a series of twisting-wheels to engage the longitudinal strands of the wire, said twisting-wheels being rotatable. The twisting-wheels are formed, preferably, with

a face-plate E², formed with sprocket-teeth e on its periphery, a sprocket-chain F engaging the sprocket-wheel C² with the toothed twisting-wheels. These twisting-wheels are ranged above and below the driving-shaft B, and one sprocket-chain serves to actuate all said twisting-wheels.

G represents a chain-tightener device, and G' a sprocket-wheel serving to direct the chain in the desired manner.

The twisting-wheels are mounted in bearings H, one of the bearings being shown in detail in Fig. 4, one of said bearings formed with a bracket-arm H'. The twisting-wheels are preferably made in two parts—the toothed face-plate E², already described, and a rear face-plate E³, bolted to the plate E², as indicated at e', the bearing H encircling the periphery of the plate E³, as indicated in Figs. 6 and 7. The plates E² of the twisting-wheel are constructed with lateral grooves or recesses (indicated at e²) to permit the longitudinal strands J of the fence being readily engaged with the twisting-wheel, the open slots e² permitting the machine to be engaged upon the longitudinal strands and disengaged therefrom in a very simple, ready, convenient, and efficient manner. Between the plates E² and E³ are preferably located rollers e³, against which the longitudinal wire strands may engage.

E' represents additional twisting-wheels constructed in a manner similar to the twisting-wheels E, already described, and rotatable in bearings H, analogous to the bearings of the twisting-wheels E, the only essential differences between the twisting-wheels E and E' being the fact that the twisting-wheels E' mesh the one with the other, and so are driven the one from the other, the twisting-wheel E', adjacent to the lower sprocket-toothed twisting-wheel, being geared therewith, inasmuch as the longitudinal strands are located nearer together toward the lower part of the fence. The bearings H are provided with bales K, serving to direct the pickets into place between the longitudinal strands.

L denotes an arm of the frame fulcrumed toward one end upon the frame A, as indicated at l, the opposite end of the arm L provided with a transversely-extended bracket L', provided with hooks l², preferably made open, as

indicated in Fig. 8, and to be readily hooked in place upon adjacent sets of longitudinal strands of the wire.

It is obviously important that the frame A should be located vertically, while the strands J of the wire on uneven or hilly ground must of necessity at times extend at an angle to the perpendicular. To permit the perpendicular location of the frame A under such circumstances, an arc-shaped bar M is engaged at its extremities with the frame A, upon which the arm L may oscillate, said arm being held in fixed position upon the arc-shaped bar, as by means of an eyebolt m and a tightening-nut m', the bar M passing through the eye of said eyebolt. By loosening up the nut m' the arm L may be raised or lowered to a desired position and then locked in position by tightening up said nut.

20 The bearing H is formed with an opening h at one side, through which the longitudinal strands may enter. First one strand of the set may be engaged through the opening h in the corresponding recess e² and then by 25 giving the twisting-wheel a half-turn the other strand may be engaged with the twisting-wheel. The frame A is made of a single piece of angle-iron, the bearings H being secured thereto.

30 My invention especially contemplates making the sprocket-teeth on the twisting-wheels or twisters E like the sprocket-teeth of a bicycle-gear and to employ a bicycle sprocket-chain in engagement therewith. The use of 35 such a chain and sprocket-toothed twisting-wheels gives a positive motion to the twisting-wheels.

The bails K compel the pickets to enter the

crotches of the wires in a vertical position throughout.

40 By this construction I am enabled to do away with a wire-stretcher and to remove the machine from the wires at any point, the single angle-iron frame and other parts contributing to this end. By unhooking the 45 bracket L' from the wires I am enabled to twist the wires up close to the finishing-post.

45 The bracket-arm H' is formed only on the lower bearing, said bracket being designed as a foot-rest for the pickets as they are put into 50 position, so that their height will be uniform.

It is evident that the rear plate or wheel E³ serves as a hub for the sprocket-wheel, as well as provides with the sprocket-wheel a 55 housing for the rollers e³.

55 What is claimed as new is—

In a fence-making machine, the combination of a frame, bearings connected with the frame, and a series of twisting-wheels to engage longitudinal fence-strands, each of said 60 twisting-wheels constructed with a toothed sprocket-wheel E², and with a hollow rear wheel E³ secured to the sprocket-wheel, the sprocket-wheel constructed with lateral 65 grooves or recesses to receive the longitudinal strands of the fence, the rear wheel serving as a hub for the sprocket-wheel and revoluble within the corresponding bearing, and 70 rollers housed within said wheels, for the purpose described.

In testimony whereof I sign this specification in the presence of two witnesses.

JAMES R. JONES.
